UNITED STATES PATENT OFFICE

CHARLES P. BANZHOF, OF LANCASTER, PENNSYLVANIA, ASSIGNOR OF THREE-FOURTHS
TO THE FIDELITY ELECTRIC COMPANY, OF LANCASTER, PENNSYLVANIA, A COR-
PORATION OF PENNSYLVANIA

BLASTING MACHINE

Application filed August 5, 1929. Serial No. 383,588.

This invention relates to electric generators of the class for setting off blasting charges and aims to provide an improved hand-operable machine for instantaneously generating the high-power current necessary to fire a plurality of charges simultaneously as well as successive or single charges.

Another important object is to provide a simple and durable machine of smallest possible size and weight for convenience in carrying.

Before describing the invention further, it is thought best to briefly explain certain factors and requirements of practice which 15 it is designed to meet.

Those who are versed in the art know that a definite current value is necessary to fire electric detonators or blasting-caps and that a fairly high voltage is required to pass a 20 current through the resistance occasioned by a number of the caps connected in series. As these caps are commercial articles varying considerably in electric characteristic, a uniform firing thereof is dependent upon the 25 heating of a small bridge-wire or equivalent by passing a current therethrough for igniting the fulminate surrounding it.

In arrangement for firing, the caps are generally connected in series so that the same 30 amount of current passes through each. If one of the series is more sensitive than the others and the current is not high enough to fire all the caps together, the more sensitive one is likely to fire and open the circuit so 35 as to prevent the remaining caps from firing. On the other hand, if one in the series requires a higher firing current than the others, it may fail to fire and explode its charge. Said failures constitute a grave danger and 40 great precaution is necessary to guard against workmen being injured by accidental ignition of unfired charges in the débris of multiple blasts.

These caps moreover have an inherent time 45 lag, i. e., they do not fire instantly as the current is applied but momentarily await heating of the bridge-wire. This time lag varies inversely with the magnitude of the current, from which it follows that sufficiently high current will reduce the lag to

a zero point and all caps in the series will be fired simultaneously. Therefore, if a current of double or more the normal firing requisite is forced through the circuit, every cap will heat and fire with only the remotest 55 possibility of failure.

From the foregoing it will be appreciated that a current generator or "blasting machine" for firing the caps must have definite operative characteristics rendering it instantaneously productive of a high magnitude current, and the purpose of this invention is to provide such a machine.

The invention will be best understood from further description with reference to the attached drawings wherein a machine of one practical embodiment thereof is illustrated.

In said drawings:

Fig. 1 is a sectional view of the machine from one side;

Fig. 2 represents a plan view as taken on the line 2—2 of the first figure;

Fig. 3 is a transverse section on the line 3—3 of the first figure;

Fig. 4 is a plan section on the line 4—4 of 75 said first figure;

Fig. 5 is a curve-chart representing approximate values of output and generation rate;

Figs. 6 and 7 are charts representing current values attained respectively with the ordinary armature and the armature of the present machine; and

Fig. 8 is a diagram of the machine circuit and its connections with charge detonators 85 or caps.

The illustrative machine is shown fitted into a metal casing 8 having a removable cover 8^a secured thereto but permitting easy access to the component parts.

This machine comprises a body member 9 in the form of a frame carrying the other parts and providing the main field or magnet of the generating plant. Said member or frame is formed of a material having high 95 permeability which also will retain a relatively high residual magnetism, such for example as the well known product of iron with relatively high content of ferric-carbide. In this instance the material is composed of a 100

special grade of cast-iron having a relatively high component of graphitized carbon and a relatively low component of phosphorus, the ferric-carbide content being commercially controlled by permitting rapid cooling after molding. Such material is used for said frame because it is found to have the particularly appropriate characteristic of retaining considerable magnetism (by virtue of the high ferric-carbide content) forming the basis for a quick building up of current, which is essential to the attainment of a high current output in machines of this kind where the operative cycle by hand impulse is so short. This feature coupled with the fact that the high component of graphitized carbon in the iron gives the material the additional characteristic of high permeability, makes it especially appropriate to this use.

The building up of magnetic flux in the field of this magnet is accelerated by a proper arrangement of field energizing windings as will presently appear, so that the residual flux with that induced by the field windings will give a high total flux resulting in high current generation, due as aforesaid to the high retentive and permeability characteristics of the material comprising the pole pieces and yoke of the field member. This is an important feature of the invention.

In the chart of Fig. 5 the approximate rates of excitation or E. M. F. generation with fields of high and low residual magnetism are represented for the purpose of comparison. In this figure the line X is the voltage curve of the new type of field forming a part of this invention and the line Y is the voltage curve of a field retaining only a small amount of residual magnetism.

Between yoke portions at one end of the aforesaid frame is an armature 10 on a shaft 11 and carrying a commutator 12. This armature and its commutator are preferably of six segment or six-part form for the purpose of producing current of more sustained value than is possible with the ordinary two-part commutator. The difference in current production between the ordinary two-part commutator and the six-part commutator used in the present machine is illustrated by the curves in Figs. 6 and 7 from which it will be seen that not only is a more sustained current value to be derived from the six-part commutator and armature divisions, but there is the added advantage of increased current in the field windings due to the fact that there is less reactance in the field windings with a current of the character mentioned.

The lower end of the armature shaft is journaled in a non-magnetic bracket 13 fastened to the frame and having extensions carrying brushes 14 within insulated holders on opposite sides of the commutator. The upper end of the armature shaft is shown

journaled in a nonmagnetic housing member 15 fastened to the upper end of the frame.

Uniting the side portions of the frame at its other end is a field magnet core 9* around which are series field windings 17 and shunt field windings 18. These windings, which accelerate the building up of magnetic flux as above stated are connected in an electrical circuit including the commutator, conductors 19 and 20, current output terminals 21 and 22, a closure switch, as represented in Fig. 8.

Said terminals are carried on a non-conductive bridge 22 within the aforesaid housing member 15. One of these terminals in this instance forms part of the aforesaid closure switch comprising flexible contact arms 21^a and 21^b insulated from each other and adapted to close the circuit therethrough on being brought in contact. To this one of the terminals, the conductor 19 including the series windings is connected, while the conductor 20 including the shunt windings connects with the other. Resting firmly in contact with these terminals are binder posts 23 carried by the casing cover for convenience in connecting the machine with the detonating circuit. This connection is represented in the aforesaid Fig. 8 wherein 24 indicates the blasting caps.

Projecting upwardly from the housing 15 is a rotary spindle 25 having bayonet joint connection with an operating handle 26. This spindle carries a segmental gear 27 which limits rotation in opposite directions by abutment against opposite sides of a lug 10 or shoulder portion 15* of the housing. Said gear carries an insulated pin 27* to engage behind and flex one arm of the closure switch against the other as the gear approaches its rotation limit in the direction indicated by the arrow in Fig. 2. The reason for placing the pin at this point will be hereinafter explained. Said gear remains normally in the position shown in Fig. 2 and is returned to such position by a spring 28 acting on its spindle.

Engaging with the segmental gear is a pinion 29 idling on a shaft 30 journaled in the housing member. Keyed to said shaft is a full gear 31 carrying a spring tensioned pawl 32 engaging the aforesaid pinion to lock the gear for rotation therewith in one direction while allowing independent movement in the other. Thus when the segmental gear is moved from normal position, its rotation will be imparted in opposite direction to the full gear through the pinion locked therewith by the pawl, but when the segmental gear is arrested or returned to normal position, the pawl simply ratchets over the pinion and permits continued rotation of the full gear.

Said full gear engages with a pinion 33 on the armature shaft to impart rotation to said armature. This multiple gear arrangement will obviously cause high speed rotation

of the armature when the spindle is turned manually by its handle and its speed will be even greater under vigorous impulse. A high magnitude current will accordingly be generated through the field windings in a fraction of time under this hand impulse.

As the duration of the operative stroke is limited while its force depends on the strength of the operator, a correct balance between his strength and the power required to overcome the inertia of the armature is necessary in order to secure the maximum output of the machine. The relation of factors to this condition may be represented by the equation

15 $\frac{MS}{T} = F$, where M represents the mass of the armature, S the speed of rotation, T the time or duration of the power impulse and F the force or power required to complete the stroke. As the factors T and F are determinable and virtually fixed by the strength of the operator, M and S are the only quantities to be taken as variable and since it is desirable that S shall be as high as possible, it naturally follows that M must be kept as low as possible. To secure this condition, the multiple gear arrangement is made in such ratio and the armature is so proportioned in weight and diameter that the average operator will 20 be able to impart a very high speed thereto within the limited extent and duration of the machine's power stroke. A high magnitude current is accordingly generated almost instantaneously through the field windings.

25 As the segmental gear nears its limit of stroke, the pin 27' thereon as previously stated engages behind and flexes one arm of the closure switch against the other to complete the circuit. The switch is thus caused to close before the segmental gear has completed its stroke for two important reasons, first, that it is desirable to close the cap circuit before the end of the power stroke so as to send out and maintain the high current volume in the circuit while continuing its generation in the machine, and second, that it prevents premature opening of the circuit by any rebound or tendency of the operator to draw back before completing the full impulse stroke.

30 From the foregoing it will be appreciated that this invention provides a greatly improved and exceedingly powerful machine in spite of its small size, whereby firing of all detonators in a blasting circuit to which it is attached will be assured.

As numerous modifications with changes in form and arrangement of parts may obviously be made without departing from the spirit and scope of the invention, the appended 35 claims are not intended to limit the same to the specific construction shown.

Having thus described my invention, what I claim as new and desire to secure by Letters Patent of the United States is:—

35 1. An electric generator of the class de-

scribed comprising in combination, a magnet of a material of high permeability and retentive of relatively high residual magnetism having a portion thereof providing a core; series and shunt field energizing windings around said core; a multi-part commutated armature rotatable in the field of said magnet; a hand-turnable spindle carrying a segmental gear in association with a speed-multiplying gearing for quickly imparting high-speed rotation to said armature with movement in one direction of limited stroke; and a normally open switch-member connected in a current-output circuit with said windings and armature, said switch-member being actuated to close by an element on the aforesaid gear before the latter reaches the end of its power stroke.

2. An electric generator of the class described embodying a magnet body of a material of high permeability and retentive of relatively high residual magnetism having a portion thereof providing a core; series energizing windings around said core; a shunt excitation coil; a multi-part commutated armature rotatable in the field of said magnet; and a current-output controlling switch-member connected in circuit with the armature, windings and coil which is closed just before the end of a short power stroke giving high-speed impulse to said armature.

3. An electric generator embodying in combination, a body member of a material having high permeability and retentive of relatively high residual magnetism forming the main field magnet and having a portion thereof providing a magnet core; series and shunt field energizing windings around said core; a multi-part commutated armature rotatable in the field of said magnet; a hand-turnable spindle carrying a segmental gear in association with speed-multiplying gearing for quickly imparting high-speed rotation to said armature with movement in one direction of limited stroke; and a normally open switch-member connected in a current-output circuit with said windings and armature, said switch-member being actuated to close just before the aforesaid gear reaches the end of its power stroke giving impulse to said armature.

4. An electric generator of the class described embodying a body member of a material of high permeability and retentive of relatively high residual magnetism having a core with energizing windings and a shunt excitation coil, a multi-part commutated armature rotatable in the field of said magnet, means including speed-multiplying gearing for imparting high-speed rotation to said armature so as to build up a high volume current in a minimum of time, and a current-output controlling switch-member connected in circuit with the armature, windings and coil and actuated to close just before the end

of an applied power stroke giving impulse to said armature.

5. An electric generator of the class described comprising in combination, a main field magnet formed of a material of high permeability and retentive of relatively high residual magnetism subject to a high degree of induction, said magnet having a portion providing a core; series and shunt field energizing windings around said core; a multi-part commutated armature rotatable in the field of said magnet; a normally open switch-member and current-output terminals connected in circuit with said windings and armature; together with hand-operated means including a segmental gear with associated speed-multiplying gearing for quickly imparting high-speed rotation to said armature with limited movement in one direction so as to build up a high magnitude current in a minimum of time by the magnetizing forces, said segmental gear functioning to close the switch-member just before it reaches the end of its impulse stroke.

10 15 20 25 30 35

6. In an electric generating machine of the character described including energizing windings and a shunt excitation coil with multi-part commutated armature and closure-switch in a current-output circuit; a main field magnet having a core around which said winding and coil are wound the one upon the other, said magnet being formed of a material having the characteristics of high permeability and retentive of relatively high residual magnetism subject to a high degree of induction accelerated by the shunt coil.

7. In an electric generating machine of the character described including energizing windings and a shunt excitation coil with multi-part commutated armature and closure-switch in a current-output circuit; a main field magnet having a core around which said winding and coil are wound the one upon the other, said magnet being formed of a material such as iron with relatively high ferric-carbide content characterized by its high permeability and retentive of relatively high residual magnetism making it subject to a high degree of induction.

8. An electric generator comprising in combination a magnet body formed with a core, said body being of a material of high permeability and retentive of relatively high residual magnetism subject to a high degree of induction; a series energizing coil and a shunt coil wound one upon the other around said core; a multi-part commutated armature rotatable in the field of the magnet body to induce a current of high and evenly sustained value in a minimum of time; a normally open switch-member and current-output terminals connected in circuit with said coils and armature; together with means including a segmental gear and associated speed-multiplying gearing for imparting high-speed rota-

tion to said armature with impulse of hand movement in one direction of limited stroke, said segmental gear carrying an element closing said switch-member just before it reaches the end of its impulse stroke so as to send out the current at the point of the armature's highest speed operation and while still generating in the windings.

In testimony whereof I affix my signature.

CHARLES P. BANZHOF.
